ELECTRON DYNAMIC BEAM CONVERGENCE
APPARATUS FOR COLOR RECEIVER
Ralph R. E'del, Lancaster, Pa., assignor to Radio Corpo-
ration of America, a corporation of Delaware
Filed July 5, 1962, Ser. No. 207,744
13 Claims. (Cl. 315—22)

This invention relates to color image display systems and particularly to means for making a plurality of electron beams of a multiple beam display device converge at all scanned points on the target electrode of said device.

An illustrative example of such a multiple beam display device is a color kinescope. Color kinescopes of the shadow mask type normally have three electron guns positioned in the neck of the kinescope and a target electrode including an apertured shadow mask located between the electron guns and a luminescent screen of phosphor dots. The dots are arranged in groups of three in register with respective apertures of the mask. Means are provided for making the three electron beams converge at the center of the scanned area of the target electrode. The three beams, after passing through the shadow mask, respectively strike three phosphor dots, each emitting light of a different color. All three beams are deflected by a common horizontal and vertical deflection system so that the beams systematically scan the kinescope target. The more the three beams are deflected from the center of the target, unless corrective measures are taken, the greater may be the misconvergence of the beams when they reach the shadow mask. It is, therefore, customary to provide dynamic electromagnetic means for correcting the misconvergence of the beams as a function of the angular deflection of the beams from the center of the kinescope target. For this purpose, current waveforms of generally parabolic shape are derived from the horizontal and vertical deflection circuits and are employed, in conjunction with three convergence electromagnets, to dynamically converge the three beams at all points of the entire scanned area of the kinescope target.

The waveforms employed must have proper shapes in order to achieve good convergence of the three beams at all points of the kinescope target. The waveform requirements may be estimated by observing the unconverted rasters of the three beams. It has been observed that color picture tube systems operating with relatively large angles of deflection, as for example 90°, require more correction at the outer edges of the scanned area when the undeflected beams are statically converged at the center of the picture area. Because of this requirement, the dynamic waveform must have greater amplitude and precision in order to effect satisfactory convergence throughout the scanned picture area. Not only are the wave-shaping requirements more severe in more recent systems having greater angles of beam deflection, but also considerably more deflecting force is needed to suitably effect the desired beam convergence.

Therefore, it is an object of the invention to provide an improved high efficiency circuit by which to effect convergence of the three electron beams of a tri-color kinescope.

The present invention is embodied in a beam convergence circuit such as that disclosed in Patent No. 2,903,622, granted September 8, 1959, to J. C. Schopp. In such apparatus the convergence electromagnet circuits appear essentially inductive to voltage pulses impressed thereon from the horizontal deflection circuits. Hence, these pulses are effectively integrated to form generally sawtooth waves which are impressed upon coils incorporated in the circuits for exciting the convergence electro-

2

magnets. A second integration of these sawtooth waves is effected by the convergence control circuits to produce the substantially parabolic current waves desired for traversal of the electromagnet windings. Circuits such as those disclosed in the Schopp patent include a resistive-capacitive circuit which functions to add a sawtooth component to the current traversing each of the convergence electromagnet windings. Such a component is used because the parabolic current waves produced in the manner described do not always have the proper shape to achieve the desired beam convergence.

The present invention is embodied in such a circuit and one feature of it comprises the connection of a unilateral conducting device (e.g. a diode) across the resistive element of the circuit by which the sawtooth wave component is produced. The connection of this unilateral conducting device is such that it is gated on (i.e. rendered conductive) during the latter part of each beam trace period. Such operation decreases the losses in the beam convergence circuits suitably to improve the wave shape of the current traversing the electromagnet winding and thereby to effect better beam convergence. During the first part of each beam trace period, the unilateral conducting device is substantially non-conducting so that the resistive element across which it is connected may be adjusted to provide an optimum discharge rate for the capacitive element in the sawtooth wave-forming circuit, thereby improving the beam convergence during the first part of each beam trace period.

30 The Schopp patent also discloses the series connection of a diode and a resistor in parallel with each beam convergence electromagnet for properly proportioning the alternating current (A.-C.) and direct current (D.-C.) components of the current waves traversing the convergence electromagnets. Another feature of the present invention, which may be used separately or in conjunction with other features, is a parallel arrangement of a diode and a resistor connected in series with the convergence electromagnet. By such an arrangement, less power is used to effect the desired beam convergence without detracting from the performance of the circuit. Thus, relatively high efficiency of operation is achieved.

For a better understanding of the invention together with additional objects, features and advantages thereof, reference will be made to the accompanying drawings in which:

FIGURE 1 is a block diagram of a color television receiver in which the present invention is embodied;

FIGURE 2 is a fragmentary sectional view of the neck portion of a shadow mask color kinescope showing the relationship of the convergence electromagnets and the electron beams respectively controlled thereby;

FIGURE 3 is a circuit diagram, partly in block form and partly in schematic form, of the beam convergence circuits embodying a unilateral conducting device in the sawtooth wave-developing circuit by which wave shaping is improved;

FIGURE 4 comprises a series of curves for use in describing the operation of the wave-shaping feature of the invention;

FIGURE 5 is a schematic circuit diagram of the convergence circuit for one electromagnet showing the wave-shaping unilateral conducting device in conjunction with the parallel connection to the electromagnet of a series diode and resistor arrangement for A.C.-to-D.C. component proportioning as disclosed in the Schopp patent; and

FIGURE 6 is a schematic circuit diagram of the convergence circuit for one electromagnet showing the wave-shaping diode feature of the invention in conjunction with the additional feature of a parallel arrangement of a diode

and resistor for A.C.-to-D.C. component proportioning connected in series with the convergence electromagnet.

Reference first is made to FIGURE 1 for a general description of a color television receiver embodying the present invention. Radiated signals received by the antenna 11 are processed in the TV receiver circuits 12 in a known manner to produce video signals representing three component colors of image to be reproduced and synchronizing signals for controlling beam deflection and for other purposes such as the production of suitable signals by which to effect convergence of the three electron beams at the target electrode of the image-reproducing color kinescope. The receiver circuits 12 may be of the type disclosed in "Color Television Service Data, 1961, No. T6," furnished by RCA Sales Corporation, Indianapolis, Indiana.

The color television receiver also includes a three beam color kinescope 13 serving as a color image-reproducing device such as a shadow mask color kinescope of the RSA type 21FBP22 or 21FJP22. The red, green and blue representative signals received from the receiver circuits 12 are impressed respectively upon electron guns 14, 15 and 16 of the tri-color kinescope 13. The three electron beams produced by these guns are deflected together over the target screen of the kinescope under the control of a deflection yoke 17. Also the beams are maintained in convergence with each other by means of a suitably energized beam convergence yoke 18, an illustrative form of which will be described subsequently.

Also derived from the receiver circuits 12 are horizontal and vertical synchronizing signals which are impressed upon a synchronizing signal separator 19. The horizontal synchronizing signals are impressed upon the horizontal deflection circuit 21 and the vertical synchronizing signals are impressed upon the vertical deflection circuit 22. The horizontal and vertical deflection circuits are connected to the deflection yoke 17 as indicated by the reference characters H—H and V—V. All of the apparatus of FIGURE 1 described up to this point may be of the same character as that disclosed in the service data previously referred to.

Signals derived from the horizontal deflection circuit 21 at the horizontal deflection rate are impressed upon horizontal convergence circuits 23, the output of which is connected to the convergence electromagnets of the convergence yoke 18. Details of such convergence circuits by which suitable convergence waves are produced will be described subsequently. Signals at the vertical deflection rate derived from the vertical deflection circuit 22 are impressed upon the vertical convergence circuits 24 for the production of suitable waves which also are impressed upon the electromagnets of the convergence yoke 18. The vertical convergence circuits are not part of the present invention and may be of a known type such as disclosed in the Schopp patent.

Reference now is made to FIGURE 2 for a description of the physical relationship of the convergence electromagnets and the electron beams controlled respectively thereby as presently embodied in commercial color television receivers. This figure is a transverse sectional view of the neck portion of a color kinescope as it appears when viewed from the luminescent screen end of the kinescope. The three electron beams 25 pass respectively between pairs of pole pieces 26, 27 and 28 located internally of the neck 29 of the kinescope 13. These pole pieces extend inwardly from the ends of substantially U-shaped cores of green, red and blue convergence electromagnets 31, 32 and 33 respectively mounted externally around the neck of the kinescope. Each of the convergence electromagnets is provided with a horizontal deflection frequency winding and with a vertical deflection frequency winding. The horizontal deflection frequency windings are designated 34G, 34R and 34B respectively for the green, red and blue electromagnets 31, 32 and 33. The vertical deflection frequency windings are designated 35G,

35R and 35B respectively for the green, red and blue electromagnets 31, 32 and 33. Energization of the electromagnet windings produces a magnetic field between the corresponding pole pieces which moves the corresponding electron beam radially. There also may be included as part of the convergence electromagnetic structure some means for effecting a static convergence of the electron beams 25. The static convergence means may be permanent magnets associated with the respective convergence electromagnets or may comprise windings on the respective electromagnets for energization by direct current of the proper amplitude and polarity to effect the desired static convergence of the electron beams. Such static convergence means is known and, since it forms no part of the present invention and is not needed for an understanding of this invention, it is not shown.

FIGURE 3 illustrates generally the connections of the horizontal convergence circuits 23 and the vertical convergence circuits 24 between the horizontal and vertical deflection circuits 21 and 22 respectively and the windings of the green, red and blue convergence electromagnets 31, 32 and 33 respectively. The horizontal deflection circuit 21 includes a deflection output tube 36 and an output transformer 37. This circuit is connected in a known manner to the horizontal deflection yoke and to the high voltage rectifier circuits as indicated. The output transformer also is provided with a secondary winding 38 in which voltage pulses at the horizontal deflection repetition rate are produced. These pulses are impressed upon the green, red and blue horizontal convergence circuits 39, 41 and 42. Each of these convergence circuits converts the voltage pulses derived from the transformer winding 38 into suitably shaped parabolic current waves for traversal of the associated horizontal deflection frequency electromagnet windings 34G, 34R and 34B.

Also, voltage pulses at the vertical deflection repetition rate derived from the vertical deflection circuit 22 are converted by the green, red and blue vertical convergence circuits 43, 44 and 45 respectively into suitably shaped parabolic current waves for traversal of the associated vertical deflection frequency electromagnet windings 35G, 35R and 35B respectively.

The present invention relates principally to the horizontal convergence circuits of which the blue horizontal convergence circuit 42 is representative. Hence, only this circuit will be described in detail. The voltage pulses derived from the secondary winding 38 of the horizontal deflection output transformer 37 are impressed upon a parabola amplitude control coil 46, the inductance of which may be varied as indicated by means such as a ferrite core movable within the coil in a known manner. The coil 46 is connected to one terminal of the winding 34B of the blue convergence electromagnet 33, the other terminal of this winding being grounded. Connected in parallel across the winding 34B is a series arrangement of a capacitor 47 and a potentiometer 48 connected as a variable resistor. The blue horizontal frequency convergence electromagnet circuit appears essentially inductive to the voltage pulses developed in the transformer winding 38 principally by reason of the inclusion of the amplitude-controlling coil 46. Hence, these pulses are effectively integrated to cause a generally sawtooth current wave to traverse the coil 46. A second integration of this sawtooth wave is effected by the convergence control circuit (principally the essentially inductive winding 34B) to produce the desired substantially parabolic current wave for traversal of the electromagnet winding 34B. In order to shape the parabolic wave to better effect the desired convergence, a sawtooth current wave component is combined with the parabolic wave. This additional sawtooth current for tilting or phasing the parabolic current traversing the electromagnet winding 34B is produced by the series arrangement of the capacitor 47 and the variable resistor 48. The amplitude of this sawtooth wave com-

ponent and hence the amount of tilting of the parabolic wave is determined by the adjustment of the variable resistor 48.

It has been found that the shape of the parabolic current wave traversing the electromagnet winding 34B for example, is not in all cases entirely adequate for effecting beam convergence in color picture tube systems operating with relatively large angles of beam deflection. The wave shaping is materially improved by connecting a unilateral conducting device such as a diode 49 in parallel across the variable resistor 48 in the polarity indicated. In prior art circuits, which did not include the diode 49, the best adjustment of the resistor 48 was a compromise between a value which would provide an adequate discharge rate for the capacitor 47 to effect satisfactory shaping of the substantially parabolic current wave during the initial portion of a trace period and which would suitably reduce circuit losses in the latter portion of a trace period to effect satisfactory wave shaping during such latter portion.

In operation of the blue horizontal convergence circuit 42 of FIGURE 3, the diode 49 is substantially non-conducting during the first portion of each horizontal beam trace over the target electrode of the color kinescope. The variable resistor 48 may be adjusted to an optimum value for effecting discharge of the capacitor 47 during the initial trace period which produces a material improvement in the shape of the parabolic current wave traversing the electromagnet winding 34B during such period. The diode 49 is conducting during the latter portion of each horizontal beam trace period, thereby decreasing the losses in the circuit. The resultant shape of the parabolic current wave through the electromagnet winding 34B is thereby improved so that better convergence of the color kinescope electron beams is achieved, particularly in those systems using color kinescopes operating with relatively wide deflection angles.

The improved shape of the parabolic current wave is illustrated by the curves of FIGURE 4. The solid line curve 51 represents the voltage developed across the convergence electromagnet such as the winding 34B of the blue electromagnet 33 in prior art circuits such as that described in the Schopp patent. This curve 51 is substantially linear throughout the entire beam trace period. As a consequence, the solid line curve 52 represents the shape of the current traversing the electromagnet winding during the beam trace period. Although the shape of this curve 52 is substantially parabolic, it has a relatively sharp peak portion 53 at the middle of the horizontal beam trace and sides which do not have sufficient steepness to effect entirely satisfactory beam convergence at the beginning and ending of the beam trace, especially in color kinescopes having relatively wide deflection angles.

The inclusion of the wave-shaping diode 49 of FIGURE 3 in the blue horizontal convergence circuit 42 alters the shape of the voltage wave across the convergence electromagnet winding as represented by the broken line curve 54 of FIGURE 4. This curve is no longer linear during beam trace intervals, but instead decreases more rapidly during the first part of trace and again more rapidly during the final part of trace. During the central portion of beam trace the voltage curve changes at a slower rate than in the first and final parts of trace. As a result, the substantially parabolic current wave which traverses the electromagnet winding has a shape substantially as illustrated by the broken curve line 55. This curve has somewhat steeper sides at both the beginning and ending of beam trace than in the previous case. This steepening results from the greater slope of the voltage wave 54 during these portions of the beam trace interval. Also, the curve 55 has a flatter peak portion during the middle of beam trace which results from the lesser slope of the voltage wave 54 during this period. The energization of the convergence electromagnet windings by substantially parabolic current waves having the shape of the

curve 55 has been found to produce significantly better dynamic beam convergence over the entire screen of a color kinescope operating with relatively wide deflection angles.

5 The novel features of the convergence circuit described with reference to FIGURE 3 also may be used in convergence circuits such as those disclosed in the Schopp Patent 2,903,622 previously referred to. FIGURE 5 illustrates such a circuit incorporating the improved wave-shaping feature of the present invention. The blue horizontal convergence circuit 42' includes the amplitude-controlling coil 46, the sawtooth wave component circuit including the capacitor 47 and the variable resistor 48 and the wave-shaping diode 49 previously described. 10 These elements function substantially in the same manner as described with reference to FIGURE 3. The voltage pulses derived from the secondary winding 38 of the horizontal deflection output transformer 37 in this case, are impressed upon the convergence circuit by a blocking 15 capacitor 61. This circuit also includes a series arrangement of a diode 62 and a resistor 63 connected in parallel with the convergence electromagnet winding 34B. The diode 62 and its associated resistor 63 serve to suitably proportion the A.C. and D.C. components of the substantially parabolic current wave impressed upon the electromagnet winding as disclosed in the Schopp patent. As disclosed in this patent, the proportioning is such that, at the troughs of the resultant parabolic wave, the current through the electromagnet winding has the same magnitude irrespective of the particular shape and peak-to-peak 20 amplitude of the wave. This makes it easier to adjust the circuitry to effect beam convergence over the entire luminescent screen of the kinescope. The blocking capacitor 61 prevents the direct current flowing through the diode 25 62 and the resistor 63 from undesirably traversing the secondary winding 38 of the horizontal output transformer 37 (FIGURE 3). Hence, the modification of the present invention shown in FIGURE 5 achieves the same results as in the Schopp patent and in addition effects the improved shaping of the substantially parabolic current wave as described previously with reference to FIGURES 3 and 4.

40 FIGURE 6 illustrates a blue horizontal convergence circuit 42'' which includes both the improved wave-shaping feature and an additional feature of the invention which enables the convergence circuit to operate in a manner to properly proportion the A.C. and D.C. components of the substantially parabolic current wave traversing the electromagnet winding at a considerably higher 45 efficiency than heretofore. As in the form of the invention shown in and described with reference to FIGURE 3, the voltage pulses derived from the horizontal deflection circuit are impressed directly upon the convergence circuit without the use of a blocking capacitor, such as the capacitor 61 of FIGURE 5. This circuit includes the amplitude-controlling coil 46, the sawtooth wave circuit including the capacitor 47 and the variable resistor 48, and the wave-shaping diode 49. All of these components are connected and operated substantially as previously 50 described.

60 Additionally there is provided a parallel arrangement of a diode 64 and a resistor 65 connected in series between the amplitude-controlling coil 46 and the convergence electromagnetic winding. The diode 64 and the resistor 65 function to properly proportion the A.C. and D.C. components of the substantially parabolic current wave traversing the electromagnet winding. By virtue of the series connection of these components with the electromagnet winding, instead of the parallel connection of the diode 62 and resistor 63 of FIGURE 5, a material saving in power is achieved. Thus, the convergence circuit 42'' of FIGURE 6 operates in a more efficient manner to achieve dynamic beam convergence in a color kinescope 65 operating with a relatively wide deflection angle.

What is claimed is:

1. In a color television receiver including, a multiple-beam color kinescope image-reproducing device, and line deflection means for deflecting said beams in a series of vertically spaced horizontal lines during successive beam trace periods to form a raster, the combination for converging said beams at all points of said raster, comprising:
 a dynamic convergence electromagnet having an energizing winding;
 10 inductive means connected with said energizing winding to cooperate with said winding in converting voltage pulses derived from said deflection means into a substantially parabolic current wave for traversal of said winding;
 means including a series arrangement of a capacitor and a resistor connected in parallel with said energizing winding to produce a sawtooth current wave component for traversal of said winding; and
 15 a unilateral conducting device connected only across said resistor in such manner as to be rendered conducting only during the latter portions of said beam trace periods to improve the shape of the substantially parabolic current wave traversing said energizing winding.
2. In a color television receiver including, a multiple-beam color kinescope image-reproducing device, and line deflection means for deflecting said beams in a series of vertically spaced horizontal lines during successive beam trace periods to form a raster, the combination for converging said beams at all points of said raster, comprising:
 a plurality of dynamic convergence electromagnets having respective energizing windings;
 means including a coil connected in series with one of said energizing windings to cooperate with said one winding in converting voltage pulses derived from said deflection means into a substantially parabolic current wave for traversal of said one winding;
 means including a series arrangement of a capacitor and a resistor connected in parallel with said one energizing winding to produce a sawtooth current wave component for traversal of said one winding; and
 20 a unilateral conducting device connected only across said resistor in such manner as to be substantially non-conducting during the initial portion of each of said beam trace periods and to be substantially non-conducting during the initial portion of each of said beam trace periods and to be conducting during the latter portion of each of said beam trace periods to improve the shape of the substantially parabolic current wave traversing said one energizing winding.
3. In a color television receiver including, a multiple-beam color kinescope image-reproducing device, and line deflection means for deflecting said beams in a series of vertically spaced horizontal lines during successive beam trace periods to form a raster, the combination for converging said beams at all points of said raster, comprising:
 a dynamic convergence electromagnet having an energizing winding, there being one such electromagnet for each of said beams;
 25 means including a coil connected in series with one of said energizing windings to cooperate with said one winding in converting voltage pulses derived from said deflection means into a substantially parabolic current wave for traversal of said one winding;
 means including a series arrangement of a capacitor and a resistor connected in parallel with said one energizing winding to produce a sawtooth current wave component for traversal of said one winding; and
 30 a unilateral conducting device connected only across said resistor in such manner as to be rendered conducting only during the latter portion of each of said beam trace periods to improve the shape of the substantially parabolic current wave traversing said one energizing winding.
4. In a color television receiver including, a multiple-beam color kinescope image-reproducing device, and line deflection means for deflecting said beams in a series of vertically spaced horizontal lines during successive beam trace periods to form a raster, the combination for converging said beams at all points of said raster, comprising:
 a dynamic convergence electromagnet having an energizing winding, there being one such electromagnet for each of said beams;
 35 means including an amplitude-controlling coil connected in series with at least one of said energizing windings to cooperate with said one winding in converting voltage pulses derived from said deflection means into a substantially parabolic current wave for traversal of said one winding;

beam trace periods to improve the shape of the substantially parabolic current wave traversing said one energizing winding.

4. In a color television receiver including, a multiple-beam color kinescope image-reproducing device, and line deflection means for deflecting said beams in a series of vertically spaced horizontal lines during successive beam trace periods to form a raster, the combination for converging said beams at all points of said raster, comprising:
 a dynamic convergence electromagnet having an energizing winding, there being one such electromagnet for each of said beams;
 means including an amplitude-controlling coil connected in series with at least one of said energizing windings to cooperate with said one winding in converting voltage pulses derived from said deflection means into a substantially parabolic current wave for traversal of said one winding;
5. In a color image display system including, a multiple-beam color image-reproducing device, and line deflection means for deflecting said beams in a series of vertically spaced horizontal lines during successive beam trace periods to form a raster, the combination for converging said beams at all points of said raster, comprising:
 a dynamic convergence electromagnet having an energizing winding;
- means including a coil connected in series with said energizing winding to cooperate with said winding in converting voltage pulses derived from said deflection means into a substantially parabolic current wave for traversal of said winding;
- means including a first resistor connected in parallel with said energizing winding to produce a sawtooth current wave component for traversal of said winding;
- a series arrangement of a diode and a second resistor connected in parallel with said electromagnet winding to proportion the direct current and alternating current components of the substantially parabolic current was so that, at the troughs of said wave, the current through said winding always has the same magnitude irrespective of the particular shape and peak-to-peak amplitude of said wave; and
- a unilateral conducting device connected across said first resistor in such manner as to be rendered conducting only during the latter portion of each of said beam trace periods to improve the shape of the substantially parabolic current wave traversing said energizing winding.
6. In a color television receiver including, a multiple-beam color kinescope image-reproducing device, and line deflection means for deflecting said beams in a series of vertically spaced horizontal lines during successive beam trace periods to form a raster, the combination for converging said beams at all points of said raster, comprising:
 a dynamic convergence electromagnet having an energizing winding;
- means including a series arrangement of a capacitor and a coil connected in series with said energizing winding to cooperate with said winding in converting voltage pulses derived from said deflection means

into a substantially parabolic current wave for traversal of said winding;
means including a series arrangement of a capacitor and a first resistor connected in parallel with said energizing winding to produce a sawtooth current wave component for traversal of said winding;
a series arrangement of a diode and a second resistor connected in parallel with said electromagnet winding to proportion the direct current and alternating current components of the substantially parabolic current wave so that, at the troughs of said wave, the current through said winding always has the same magnitude irrespective of the particular shape and peak-to-peak amplitude of said wave; and

5 a unilateral conducting device connected across said first resistor in such manner as to be substantially non-conducting during the initial portion of each of said trace periods and to be rendered conducting during the latter portion of each of said beam trace periods to improve the shape of the substantially parabolic current wave traversing said energizing winding;

7. In a color television receiver including, a multiple-beam color kinescope image-reproducing device, and line deflection means for deflecting said beams in a series of vertically spaced horizontal lines during successive beam trace periods to form a raster,

the combination for converging said beams at all points of said raster, comprising:

a dynamic convergence electromagnet having an energizing winding;

means including a series arrangement of a capacitor and a variable inductance coil connected in series with said energizing winding to cooperate with said winding in converting voltage pulses derived from said deflection means into a substantially parabolic current wave for traversal of said winding, said coil serving to control the amplitude of said parabolic wave;

means including a series arrangement of a capacitor and a variable resistor connected in parallel with said energizing winding to produce a sawtooth current wave component for traversal of said winding, said resistor serving to control the amplitude of said sawtooth wave component;

40 a series arrangement of a diode and a resistor connected in parallel with said electromagnet winding to proportion the direct current and alternating current components of the substantially parabolic current wave so that, at the troughs of said wave, the current through said winding always has the same magnitude irrespective of the particular shape and peak-to-peak amplitude of said wave; and

50 a diode connected across said variable resistor in such polarity as to be rendered conducting only during the latter portion of each of said beam trace periods to improve the shape of the substantially parabolic current wave traversing said energizing winding.

8. In a color image display system including, a multiple-beam color image-reproducing device, and line deflection means for deflecting said beams in a series of vertically spaced horizontal lines during successive beam trace periods to form a raster,

the combination for converging said beams at all points of said raster, comprising:

a dynamic convergence electromagnet having an energizing winding;

means including a coil connected in series with said energizing winding to cooperate with said winding in converting voltage pulses derived from said deflection means into a substantially parabolic current wave for traversal of said winding, said coil serving to control the amplitude of said parabolic wave;

means including a first resistor connected in parallel with said energizing winding to produce a sawtooth current wave component for traversal of said winding;

a first unilateral conducting device connected across said first resistor in such manner as to be rendered conducting only during the latter portion of each of said beam trace periods to improve the shape of the substantially parabolic current wave traversing said energizing winding; and

5 a parallel arrangement of a second unilateral conducting device and a second resistor connected in series with said electromagnet winding to proportion the direct current and alternating current components of the substantially parabolic current wave so that, at the troughs of said wave, the current through said winding always has the same magnitude irrespective of the particular shape and peak-to-peak amplitude of said wave, whereby to effect convergence of said beams with a high degree of efficiency over relatively large angles of beam deflection.

9. In a color television receiver including, a multiple-beam color kinescope image-reproducing device, and line deflection means for deflecting said beams in a series of vertically spaced horizontal lines during successive beam trace periods to form a raster,

the combination for converging said beams at all points of said raster, comprising:

a dynamic convergence electromagnet having an energizing winding;

means including a coil connected in series with said energizing winding to cooperate with said winding in converting voltage pulses derived from said deflection means into a substantially parabolic current wave for traversal of said winding;

means including a series arrangement of a capacitor and a first resistor connected in parallel with said energizing winding to produce a sawtooth current wave component for traversal of said winding;

30 a unilateral conducting device connected across said resistor in such manner as to be rendered conducting only during the latter portion of each of said beam trace periods to improve the shape of the substantially parabolic current wave traversing said energizing winding; and

35 a parallel arrangement of a diode and a second resistor connected in series with said electromagnet winding to proportion the direct current and alternating current components of the substantially parabolic current wave so that, at the troughs of said wave, the current through said winding always has the same magnitude irrespective of the particular shape and peak-to-peak amplitude of said wave, whereby to effect convergence of said beams with a high degree of efficiency over relatively large angles of beam deflection.

10. In a color television receiver including, a multiple-beam color kinescope image-reproducing device, and line deflection means for deflecting said beams in a series of vertically spaced horizontal lines during successive beam trace periods to form a raster,

the combination for converging said beams at all points of said raster, comprising:

a dynamic convergence electromagnet having an energizing winding;

means including a variable inductance coil connected in series with said energizing winding to cooperate with said winding in converting voltage pulses derived from said deflection means into a substantially parabolic current wave for traversal of said winding, said coil serving to control the amplitude of said parabolic wave;

means including a series arrangement of a capacitor and a variable resistor connected in parallel with said energizing winding to produce a sawtooth current wave component for traversal of said winding, said resistor serving to control the amplitude of said sawtooth wave component;

a diode connected across said variable resistor in such polarity as to be rendered conducting only during the

latter portion of each of said beam trace periods to improve the shape of the substantially parabolic current wave traversing said energizing winding; and a parallel arrangement of a diode and another resistor connected in series with said electromagnet winding to proportion the direct current and alternating current components of the substantially parabolic current wave so that, at the troughs of said wave, the current through said winding always has the same magnitude irrespective of the particular shape and peak-to-peak amplitude of said wave, whereby to effect convergence of said beam with a high degree of efficiency over relatively large angles of beam deflection.

11. In a color image display system including, a multiple-beam color image-reproducing device, and line deflection means for deflecting said beams in a series of vertically spaced horizontal lines during successive beam trace periods to form a raster,

the combination for converging said beams at all points of said raster, comprising:

a dynamic convergence electromagnet having an energizing winding;

means connected with said energizing winding to cooperate with said winding in converting voltage pulses derived from said deflection means into a substantially parabolic current wave for traversal of said winding; and

a parallel arrangement of a unilateral conductive device and resistive means connected in series with said electromagnet winding to proportion the direct current and alternating current components of the substantially parabolic current wave so that, at the troughs of said wave, the current through said winding always has the same magnitude irrespective of the particular shape and peak-to-peak amplitude of said wave, whereby to effect convergence of said beams with a high degree of efficiency.

12. In a color television receiver including, a multiple-beam color kinescope image-reproducing device, and line deflection means for deflecting said beams in a series of vertically spaced horizontal lines during successive beam trace periods to form a raster,

the combination for converging said beams at all points of said raster, comprising:

a dynamic convergence electromagnet having an energizing winding;

inductive means connected in series with said energizing winding to cooperate with said winding in converting voltage pulses derived from said deflection means into a substantially parabolic current wave for traversal of said winding; and

a parallel arrangement of a unilateral conductive device and a resistor connected in series with said electromagnet winding to proportion the direct current and alternating current components of the substantially parabolic current wave so that, at the troughs of said wave, the current through said winding always has the same magnitude irrespective of the particular shape and peak-to-peak amplitude of said wave, whereby to effect convergence of said beams with a high degree of efficiency.

13. In a color television receiver including, a multiple-beam color kinescope image-reproducing device, and line deflection means for deflecting said beams in a series of vertically spaced horizontal lines during successive beam trace periods to form a raster,

the combination for converging said beams at all points of said raster, comprising:

a dynamic convergence electromagnet having an energizing winding;

means including a coil connected in series with said energizing winding to cooperate with said winding in converting voltage pulses derived from said deflection means into a substantially parabolic current wave for traversal of said winding; and

a parallel arrangement of a diode and a resistor connected in series between said coil and said electromagnet winding to proportion the direct current and alternating current components of the substantially parabolic current wave so that, at the troughs of said wave, the current through said winding always has the same magnitude irrespective of the particular shape and peak-to-peak amplitude of said wave, whereby to effect convergence of said beams with a high degree of efficiency.

UNITED STATES PATENT OFFICE
CERTIFICATE OF CORRECTION

Patent No. 3,187,218

June 1, 1965

Ralph R. E'del

It is hereby certified that error appears in the above numbered patent requiring correction and that the said Letters Patent should read as corrected below.

Column 3, line 20, for "RSA" read -- RCA --; column 7, lines 47 to 49, strike out "and to be substantially non-conducting during the initial portion of each of said beam trace periods" column 8, line 52, for "was" read -- wave --.

Signed and sealed this 7th day of December 1965.

(SEAL)
